UNITED STATES PATENT OFFICE.

JOHN J. ZEITZ, OF CLEVELAND, OHIO, ASSIGNOR TO THE AMERICAN MULTIGRAPH COMPANY, OF CLEVELAND, OHIO, A CORPORATION OF OHIO.

PAPER-FEEDING MECHANISM.

1,046,245.

Specification of Letters Patent. Patented Dec. 3, 1912.

Application filed March 19, 1908. Serial No. 421,965.

To all whom it may concern:

Be it known that I, JOHN J. ZEITZ, a citizen of the United States, residing at Cleveland, in the county of Cuyahoga and State 5 of Ohio, have invented a certain new and useful Improvement in Paper-Feeding Mechanism, of which the following is a full, clear, and exact description, reference being had to the accompanying drawings.

10 The object of this invention is to provide a simple, effective and accurately controlled paper feed device for printing mechanisms.

The invention is in the nature of an improvement on the feeding mechanism shown, 15 described and claimed in Patent No. 846,992 of H. C. Gammeter, the present mechanism being broadly covered by that patent and also by Patent No. 812,735 of H. C. Gammeter. In Patent No. 846,992 referred to, 20 there are a pair of feed rolls and mechanism engaging one end of one of them to move it into or out of engagement with the other to control the feed. This mechanism is satisfactory under normal conditions, but 25 under conditions where the material fed is thicker at one side than the other, as, for example, an envelop, the shiftable roller is liable to roll with sufficient unevenness to cause one edge of the paper to be gripped 30 with greater force than the other, thereby causing uneven feed.

The present invention is designed to positively lift or lower both ends of the roller together notwithstanding the fact that the 35 actuating mechanism is at one end only. This enables an absolutely true and accurate feed.

The invention is well adapted for a printing device of the type embodied in the Gammeter multigraph, wherein there is a rotary drum adapted to carry parallel lines of individual assembled type and a rotary impression platen co-operating therewith.

The invention is hereinafter more fully 45 explained and its essential characteristics set out in the claims.

In the drawings, Figure 1 is a vertical section through a Gammeter printing machine; Fig. 2 is an enlarged vertical section 50 at the end of the feed mechanism looking from the opposite direction to Fig. 1; Fig. 3 is a portion of a front elevation showing the extensible cam operating the feeding mechanism; Fig. 4 is a plan of the feeding mechanism; Fig. 5 is a vertical section

through the platen and adjacent parts showing also the paper stripper; Fig. 6 is a perspective of the shiftable feed roller, its yoke and the paper strippers.

Referring to the parts by reference numerals, 10 represents the base and 11 and 12 the side plates of the frame. Above this base and between the side plates is the rotary drum 13 on a shaft 14 journaled in the plates and having on its end a crank or other means 15 by which it may be rotated. This drum may be formed to carry any printing surface, as, for example, individual type arranged in parallel lines, as is well understood, it being deemed unnecessary to show any particular means in the drawing. Within a recess in the drum are shown ribbon spools 16 which are adapted to carry ends of the ribbon extending intermediately across the type on the drum. Beneath the drum and projecting upwardly through an opening 20 in the base plate is the impression platen 21 which is geared by gears 22 and 23, with the drum. This much of the construction is a common one in Gammeter printing machines, it being understood that the paper to be printed is fed between the printing drum and the impression platen and impressed by the form on the drum through the ribbon.

To feed the paper accurately I provide the following mechanism: First, a continuously rotating lower roll 25 connected by gears 26 and 27 with the platen gear 22; second, a shiftable roller 29 above the roller 25, which is adapted to be brought into engagement with the roller or held out of engagement; and third, stop fingers 30 which are adapted to stand normally in the path of the paper, forming a positive stop for it but are automatically moved out of the way when the rollers come into engagement. This much of the construction is shown in Gammeter Patent No. 846,992. The roll 25 is preferably composed of rubber sections on a shaft, while the shiftable roll 29 is preferably a single piece of steel formed sectionally, as shown. My mechanism relates to the means by which the shiftable roller is accurately shifted.

The shiftable roller 29 has a shaft, or gudgeons 31 loosely journaled in a pair of levers 32 and 33 which are pivoted at 35 and 36 at the rear of the roller and extend to the front of the roller and there have 110

connected with them springs 34 the lower ends of which are connected to the frame. These springs tend to draw the roller downwardly evenly on to the continuously revolving roller 25. 38 represents a yoke, preferably consisting of a thin bar standing on edge. This yoke extends parallel and in front of the roller 29 and across its ends. The gudgeons 31 extend loosely through openings 39 in the yoke and the yoke is pivoted on the same pins 35 and 36 which pivot the arms 32 and 33. At one end of the yoke, as shown at 40, it extends rearwardly from its pivot and there carries a roller 41, this rearward extension of the yoke being preferably off-set as shown in Figs. 4 and 6, to bring the roller into convenient position.

On the drum is an extensible cam formed of two rings, 46 and 47. Either of these rings is adapted to act on the roller 41 and thereby depress it, raising the forward portion of the yoke and thereby raising the roller 29 out of engagement with the roller 25. Whenever such action takes place a suitable stop 50 on the under side of the forward portion of the arm 32 moves away from and releases a rock arm 51 on a rock shaft 52 on which the arms 30 are mounted, this action allowing the spring 54 to rock the shaft 52 to raise the arms 30 into the path of the paper.

It will be seen that, by reason of the cam and roller acting on the yoke instead of directly on the arm 32, movement is evenly communicated to each end of the roller 29 so that it is accurately lifted and not twisted. The feature of having two cams which may be adjusted to vary the effective cam length is covered by an application No. 396,571 of H. C. Gammeter. It enables the time during which the feed rollers are held out of engagement to be accurately controlled.

The pins 35 and 36 on which the arms 32 and 33 and the yoke are pivoted are mounted in blocks 60 which are held to the base plate of the frame, suitable screws holding the blocks to the base plate and the pins in the blocks. This allows the easy positioning and adjustment of the parts as well as their convenient removal. The pin 35 is preferably provided with a head 61 by which it may be removed from the outside of the machine, while the pin 36 may be removed from the inside. This allows the yoke and feed roller to be taken out. The removal of these parts from the blocks 60, which act as distance pieces between the arms and the yoke, allows the roller to be shifted in one direction or the other, so that it may be taken out of the yoke.

To properly control the edges of the paper while it is passing to and from the platen, I provide marginal guides consisting of a pair of members 67 located at each end of the

platen and presenting each a strip 68 lying above the paper and a strip 69 below the paper. The paper is fed between these strips, so that its edges are effectively guided. The strips are held in place by screws 70 passing through a common bent-down portion of the strips into the base plate 10. At their front ends the strips 68 and 69 flare from each other, the lower one 69 curving downwardly and passing into the opening 20 in the base plate, as shown more particularly in Fig. 5. The upper member 68 extends beneath the inwardly projecting portions 65 of the pins 35 and 36 as the case may be, the extreme end of the strip 68 bending upwardly in front of these pin projections. The result of this construction is that a very effective guide and guard is provided for the edges of the paper, receiving the same immediately as it passes from the feeding rolls and insuring the guiding of the paper directly to the platen and printing drum.

I claim:

1. The combination, with a pair of co-operating feed rollers at least one of which is bodily movable, of a rigid movable member acting on both ends of the roller last referred to and loosely connected therewith at one end at least, enabling the axis of said roller to change its position with reference to said member, and springs acting independently on the two ends of such roller.

2. The combination of a pair of feeding rollers, mechanism spanning the length of one of such rollers and adapted to operate simultaneously on both ends thereof and loosely connected therewith at one end at least, enabling such end to move bodily with reference to said mechanism, and springs opposing such operation and acting independently on the two ends of such roller.

3. The combination of a printing drum, an impression platen, a pair of feed rollers, a pivoted yoke for moving both ends of one of the feed rollers, the connection between the yoke and at least one end of such roller being loose and allowing said roller to move bodily with reference to the yoke, mechanism adjacent to one end only of the feed rollers for automatically operating said yoke, and springs acting independently of the yoke and independently of each other on the two ends of the roller last referred to.

4. The combination of a printing member and an impression platen, a pair of co-operating feed rollers to feed the paper to the impression line, mechanism for shifting one of the feed rollers, said mechanism including a rigid movable bar acting on both ends of such roller and loosely connected therewith at one end at least, enabling such roller to move bodily with reference to the bar, springs acting independently on the two ends of such roller, and means acting on one

- end of the shifting mechanism for operating it.
5. The combination of a printing member and an impression platen, a pair of coöperating feed rollers, a yoke pivoted independently of the printing member and platen and connected with both ends of one feed roller, at least one of such connections being loose, enabling the axis of said roller to change its 10 position with reference to said member, a pair of springs acting independently on the two end portions of the last mentioned feed roller, and means on the printing member for operating said yoke.
15. The combination of a pair of feed rollers, springs adjacent to each end of one of the feed rollers tending to move it with reference to the other roller, mechanism extending parallel with the first-mentioned roller 20 and loosely engaging both ends thereof enabling relative movement bodily of such ends, and means for operating said mechanism to move the roller.
25. The combination of a printing member and an impression platen, a pair of coöperating feed rollers, a yoke loosely connected with both ends of one feed roller, springs acting on said feed roller, a cam roller carried by said yoke, and a cam operating on 30 said cam roller.
35. The combination of a rotary printing drum, an impression platen, a pair of feed rollers, springs adjacent to each end of one of the feed rollers tending to move it into engagement with the other roller, mechanism extending parallel with the first-mentioned feed roller and engaging both ends thereof, and means for operating said mechanism to separate the rollers.
40. The combination of a pair of feed rollers, means for rotating one of them, a pair of pivoted arms in which the other roller is journaled near its ends, springs acting on 45 said arms tending to draw the rollers into engagement, a pivoted yoke adapted to simultaneously move both ends of the roller, and means for operating the yoke.
50. The combination of a pair of feed rollers, a pair of pivoted arms in which one of said rollers is mounted, a yoke pivoted adjacent to the pivots of the arms, the shaft of said roller extending loosely into 55 said yoke, and means for operating the yoke.
55. The combination of a rotary printing drum, an impression platen, a pair of feed rollers, levers carrying the end of one of the
- feed rollers, springs acting on said levers tending to move this feed roller into engagement with the other, a yoke adapted to move both ends of the feed roller in the direction 60 opposite to the action of the springs, a roller on said yoke, and a cam on the drum adapted to engage such roller.
12. The combination, with the printing drum and platen, a pair of feed rollers, a pair of pivoted arms in which one of the rollers is journaled, a yoke extending parallel with the feed roller and across the ends thereof, the shaft of one of the rollers extending loosely into the yoke, said yoke being pivoted adjacent to the pivots of the arms, one end of the yoke extending beyond its pivot, a roller carried by the yoke at such point, and a cam on the drum coöperating 70 with said roller.
13. The combination of a printing drum and an impression platen, a pair of feed rollers, one of which is mounted on pivoted arms, a pair of edge guides for the paper leading from the feed rollers to the platen, 80 the pivot pins of said arms extending across said edge guides.
14. The combination of a frame having a base plate with an opening in it, a platen journaled below the base plate and extending upwardly through it, edge guides at the end of the platen each having a pair of plates, the lower one of which extends downwardly into such opening, a printing member located above the platen, a pair of paper 90 feed rollers in front of the platen, one of said rollers being mounted on pivoted arms, pivot pins for such arms extending across the upper members of the edge guides, said upper members being bent upwardly in 95 front of the pins whereby a converging guide is provided for the edge of the paper.
15. The combination of a rotary printing drum, a rotary impression platen, a pair of coöperating feed rollers, a pair of independently pivoted arms in which the ends of one of the feed rollers are carried, springs acting on said arms independently, and a rigid member extending in part along said roller, and acting simultaneously on both ends 105 thereof.

In testimony whereof, I hereunto affix my signature in the presence of two witnesses.

JOHN J. ZEITZ.
